AGGREGATE MOISTURE ELIMINATOR

Albert C. Kennedy, Malvern, Ark.

Application March 29, 1939, Serial No. 264,867

8 Claims. (Cl. 94—39)

My invention relates to road building machinery, and has among its objects and advantages the provision of an improved aggregate moisture eliminator.

In the construction of roadbeds, particularly beds having a finished surface of bituminous material, the problem of moisture elimination is the cause of considerable delay and expense in the construction of such roads. It is common practice to make use of an aggregate placed on a foundation base. The finished surface is applied to the aggregate, but finishing material such as asphalt cannot be applied until the aggregate is devoid of moisture. After laying of the aggregate, it frequently happens that rain will wet the road stretch and delay further work on the roadbed until the moisture has been eliminated. The aggregate may be turned and mixed to expose the material to the wind and sun for drying purposes so as to facilitate the application of asphalt. Such a method depends entirely upon weather conditions and is the cause of considerable delay and expense even under the best of weather conditions.

Accordingly, an object of my invention is to provide a machine adapted to eliminate moisture from the aggregate so as to eliminate costly delays incident to the application of bituminous material to the roadbed under present methods.

A further object is to provide a machine embodying a series of plows for stirring and mixing the aggregate together with a series of burners so related to the plows as to effectively eliminate moisture from the mass of aggregate stirred and mixed by the plows. The plows are staggered in such manner as to effectively mix the mass of aggregate to a predetermined depth and the burner devices are so arranged as to positively direct heat onto the stirred and mixed mass of aggregate. The machine is designed to process a relatively large area of roadbed and may be drawn through the medium of any suitable source of power in such manner as to move at a variable speed dependent upon the degree of moisture elimination necessary for a given stretch of roadbed.

Another object is to provide a machine of the type described in which aggregate stirring plows are associated with direct heat application means for the aggregate exposed by the plows and in which the plows are provided with means for effectively adjusting the same for depth.

In the accompanying drawings:

Figure 1 is a top plan view of my invention;

Figure 2 is a sectional view along the line 2—2 of Figure 1;

Figure 3 is a sectional view along the line 3—3 of Figure 1;

Figure 4 is a sectional view along the line 4—4 of Figure 3;

Figure 5 is a view taken from the position indicated by line 5—5 of Figure 1; and

Figure 6 is a perspective view of one of the plows separated from its supporting structure 10 for the sake of clearness.

In the embodiment selected to illustrate my invention, I make use of a main frame 10 which may comprise side members 12 and end members 14 with the members cut diagonally at their ends and welded into a unitary structure, as at 16. Members 12 and 14 may comprise standard I-beams. To the members 12 I bolt bearings 18 which rotatably carry a crank axle 20 on the ends of which are rotatably mounted supporting 20 wheels 22.

In advance of the frame 10 I locate a truck 24 which comprises an axle 26 provided with supporting wheels 28, and the axle is provided with a draw bar 30 provided with a plate 32 having an opening 34 to facilitate connection with a tractor, or other type of power, for pulling the device over the roadbed being treated. Referring to Figure 2, axle 26 is provided with a plate 36 upon which I position a plate 38 rotatably related to the bed plate 36 by reason of a bolt 40 which extends through aligned openings in the two plates. To the plate 38 I weld the forward ends of diverging beams 42, and the rear ends of the beams are provided with wings 44 positioned between flanges 46 welded to the members 12. Wings 44 and the flanges 46 are provided with aligned openings for the reception of connecting bolts 48 so that the rear ends of the beams 42 are pivotally connected with the frame 10.

Upon the beams 42 I bolt bearings 50 which rotatably support a shaft 52 having arms 54 fixedly related to its ends. The outer ends of the arms 54 are connected with supporting chains 56 which have their lower ends connected with eyes 58 secured to the forward member 14. Thus, rotation of the shaft 52 will actuate the chains 56 for raising and lowering the forward end of the frame 10.

Means for rotating the shaft 52 comprises a worm gear 60 keyed to the shaft, see Figure 2. Worm gear 60 meshes with a worm 62 keyed to a control shaft 64 having its forward end rotatably journaled in a sectional housing 66 which en-

closes the worm gear 68 and the worm 62. The sections 68 of the housing 66 are secured into a unitary structure by bolts 70. The rear end of the control shaft 64 is rotatably journaled in a bearing 72, and the end of the shaft is keyed to a bevel gear 74 arranged in mesh with a bevel gear 76 keyed to a shaft 78 rotatably supported in bearings 80 at the upper end of a bracket 82. Bearing 72 is interconnected with a supporting bearing 84 mounted loosely on the shaft 78 through the medium of an arm 86. To the shaft 78 I key a hand wheel 88 through the medium of which the shaft 78 may be rotated for operating the shaft 64 and raising and lowering the forward end of the frame 10 in accordance with road demands.

Rotation of the crank axle 20 for raising and lowering the rear end of the frame 10 comprises a shaft 90 having threaded connection with a connecting member 92 having pivots 94 loosely connected with the upper ends of arms 96 fixedly connected at their opposite ends with the crank axle 20. Shaft 90 is rotatably journaled in a bearing 98 and is provided with a bevel gear 100 arranged in mesh with a bevel gear 102 keyed to a shaft 104 rotatably journaled in bearings 106 at the upper end of a bracket 108. Bearing 98 is supported through the medium of an arm 110 fixedly related to a bearing 112 loosely connected with the shaft 104. Rotation of the shaft 104 is consummated through the medium of a hand wheel 114 keyed to the shaft. Thus, rotation of the shaft 104 imparts rotary motion to the shaft 90 for oscillating the arms 96, which in turn operates the crank axle 20 for raising and lowering the rear end of the frame 10 in accordance with road demands. Brackets 82 and 108 are bolted to a floor 116, as at 118.

Frame 10 is provided with a plurality of transverse beams 120, which beams have their ends welded to the webs 122 of the frame members 12, as at 124 in Figure 3. According to Figure 1, the beams 120 are equally spaced longitudinally of the frame 10, and each beam carries a plurality of roadbed working tools 126. All the tools are identical in construction and operation so that the description of one will refer to all.

Referring to Figures 3, 4 and 6, the tool 126 of Figure 6 comprises an aggregate plowing blade or shovel 128 having a convex leading face 130 and tapered gently to a point 132. Blade 128 is fixedly related to a shank 134 comprising a strap bent back upon itself at 136 with the ends of the strap welded at 138 to the face 140 of the beam 120. The legs of the shank 134 are spaced for the reception of headed bolts 142 passing through openings in the blade 128, and the bolts 142 are provided with nuts 144 through the medium of which the blade may be fixedly clamped to the shank, as illustrated in Figure 4. Thus, the blade 128 may be adjusted longitudinally of the shank 134 and fixedly connected therewith in different positions.

While the tools 126 are identical in construction and operation, the tools associated with one beam are offset with respect to the tools associated with the adjacent beam in such manner as to plow furrows midway between the furrows plowed by the proceeding tools so as to effectively distribute the plowing action throughout the entire mass of the aggregate. The blades 128 incline slightly forwardly in the direction of their pointed ends 132 and are of such width and convexity as to effectively open the aggregate as the tools plow therethrough. The depth of the plowing ac-

tion is effectively controlled through manipulation of the hand wheels 88 and 114.

Each gang of tools 126 is associated with a series of burners 146. Figure 1 illustrates the burner units 146 as being mounted on shafts 156 extending transversely of the frame 10 immediately adjacent their respective beams 120 so as to closely associate the burners with their respective tools 126. Figure 3 illustrates one of the shafts 156, which shaft has its ends rotatably journaled in bearings 150 bolted at 152 to the frame members 12. All the shafts 156 and the burner units 146 are of the same construction and operate in the same manner so that the description of one will apply to all. Referring to Figures 3 and 4, particularly Figure 4, the burner unit 146 comprises a burner tube 148 having a bracket 151 bolted to a clamp 153 through the medium of bolts 154. Clamp 153 embraces the shaft 156 so as to fixedly relate the burner unit 146 to the shaft. A lever 158 is keyed to the shaft 156 and extends upwardly to be latched in the positions of Figures 3 and 4 through the medium of latch bars 160 pivotally connected at 162 to the frame members 12. Latch bars 160 may be pivoted out of the path of the lever 158 to permit rotation of the shaft 156 and adjustment of the burner units 146 fixedly related to the shaft. Figure 3 illustrates the latch bars 160 as being pivotally connected with one of the frame members 12 sufficiently far inwardly thereof to afford support for the bars in their horizontal positions, so that the lever 158 will be latched between the two bars.

Referring to Figure 4, burner tube 148 is positioned slightly in the rear of its associated tool 126, and the tube is provided with a cap 164 provided with a slot 166 for the admission of air into the tube. Cap 164 is telescopically related to the tube 148 to be adjusted relatively thereto for varying the air inlet capacity of the slot 166, and the cap 164 may be secured in adjusted positions through the medium of a set screw 168.

A fuel tube 170 is associated with the tube 148 and is bent to provide a reach 172 extending into the tube 148 through its lower end, with the upper end of the reach 172 bent downwardly of the tube, as at 174. The lower end of the tube 148 is perforated at 176. Means for supplying fuel in the nature of oil to the tube 170 comprises a flexible tube 178 connected at one end with the tube 170 and its other end connected with a valve 180 interposed in a pipe line 182 extending transversely of the frame 10. Figure 1 illustrates the transverse pipe lines 182 as being connected with pipe lines 184 which extend longitudinally of the frame 10 adjacent the side members 12. The rear ends of the pipes 184 are interconnected by a pipe 186, which pipe is connected with fuel supply tanks 188 through the medium of branches 190 provided with valves 192. Thus, each series of burners 146 is provided with one transverse pipe 182, and each burner is provided with one valve connection 180 with its respective pipe 182. Each pipe 182 has fuel delivery communication with both of the pipes 184, the latter having fuel delivery communication with the supply tanks 188.

Referring to Figure 4, the tube 170 is fixedly related to the burner tube 148 by brackets 194 which may be welded to the two tubes. The burner tube 148 is provided with a generating pan 196 which is fixedly related to the burner tube through the medium of a bracket 198 which

may be welded to the burner tube and the generating pan. For generating purposes, shaft 156 is rotated through the medium of its lever 158 to bring the pan 196 to the dotted line horizontal position. Thus, the pan may be provided with

a supply of fuel within its horizontal position and the fuel ignited for bringing the burner unit to the necessary high temperature for vaporizing the fuel supplied thereto from the tanks 188. Flexible connection 178 permits shifting of the burner unit to the horizontal position of Figure 4.

Floor 116 has its forward margin welded to the rear cross member 14 and the floor is additionally supported through the medium of diagonal braces 200 having their forward ends welded to the rear cross member 14 and their rear ends welded to the rearward margins of the floor. Upon the floor 116 I mount an air pressure pump 202 which may be operated through the medium of a lever 204 for placing the fuel in the supply tank 188 under pressure. Pump 202 has communication with a pipe 206 which communicates with the two supply tanks 188 near their upper ends. Obviously, an air pressure pump of the motor driven type may also be mounted on the floor 116.

To the two side members 12 I connect vertical wings 208. The wings are fixedly related to the side members through the medium of angle brackets 210 which may be welded to the wings 208 and the side members 12. Partly overlapping the lower margins of the wings 208 are two plates 212 which may be welded to the wings. Replaceable wing elements 214 have partial overlapping relation with the plates 212, and are detachably connected with the plates through the medium of bolts 216. Wing elements 214 extend downwardly slightly below the plowing depth of the shovels 128 and the wing structure constitutes walls which function to prevent spreading of the heat beyond the road area effectively stirred by the shovels 128. Wing elements 214 are subjected to considerable wear and are therefore made replaceable.

In operation, shovels 128 operate to effectively agitate the aggregate and expose it in such manner as to be effectively heated by the burner units 146. The burner units are so distributed as to provide the direct application of heat throughout the entire aggregate area stirred by the shovels 128, and the shovels are so arranged as to effectively expose all the aggregate stirred by the shovels to direct heat. Thus, I provide means for effectively drying the aggregate so as to facilitate application of the road surfacing material. Shovels 128 are adjustably related to their respective shanks 134 so as to secure precise positioning and adjustment to compensate wear. In addition, the frame 10 is mounted so as to be adjusted for elevation to the end that the tools 126 may effectively stir the aggregate to a predetermined depth. Shovels 128 in their staggered relation stir the aggregate in such manner as to expose all the aggregate to a given depth to direct heat.

Supply tanks 188 are provided with removable caps 218 for filling purposes. Hand wheels 88 and 114 are closely associated with the pump lever 204, and the hand wheels are located rearwardly of the tool and burner devices so that the operator takes a position where he may conveniently observe the operation of the tools and burners.

Having thus described certain embodiments of my invention in detail, it is, of course, understood

that I do not desire to limit the scope thereof to the exact details set forth except in so far as those details may be defined in the appended claims.

I claim:

1. An aggregate moisture eliminator comprising a portable frame structure adapted to be moved over a bed of aggregate, aggregate stirring tools carried by the frame structure, burner means associated with the aggregate stirring tools for heating the aggregate stirred by the tools, to eliminate moisture from the aggregate, normally upright generator pans fixedly related to the burner means, and means for shifting the burner means to bring the generator pans to horizontal positions and subsequently moving the burner means to latched normal positions.

2. An aggregate moisture eliminator comprising a wheel supported frame, beams extending transversely of the frame, aggregate stirring plows carried by said beams, with the plows of one beam offset laterally of the plows of an adjacent beam, transverse shafts carried by the frame in the rear of said beams, and burners mounted on said shafts rearwardly of the stirring plows for heating the aggregate stirred by the plows, to eliminate moisture from the aggregate.

3. An aggregate moisture eliminator comprising a wheel supported frame, beams extending transversely of the frame, aggregate stirring plows carried by said beams, with the plows of one beam offset laterally of the plows of an adjacent beam, transverse shafts carried by the frame in the rear of said beams, burners mounted on said shafts rearwardly of the stirring plows for heating the aggregate stirred by the plows, to eliminate moisture from the aggregate, and means for moving the frame vertically to vary the stirring depth of said plows.

4. An aggregate moisture eliminator comprising a wheel supported frame, beams extending transversely of the frame, aggregate stirring plows carried by said beams, with the plows of one beam offset laterally of the plows of an adjacent beam, transverse shafts carried by the frame in the rear of said beams, burners mounted on said shafts rearwardly of the stirring plows for heating the aggregate stirred by the plows, to eliminate moisture from the aggregate, fuel supply means carried by the frame, and fuel connections between the fuel supply means and said burners.

5. An aggregate moisture eliminator comprising a wheel supported frame, beams extending transversely of the frame, aggregate stirring plows carried by said beams, with the plows of one beam offset laterally of the plows of an adjacent beam, transverse shafts carried by the frame in the rear of said beams, burners mounted on said shafts rearwardly of the stirring plows for heating the aggregate stirred by the plows, to eliminate moisture from the aggregate, fuel supply means carried by the frame, fuel connections between the fuel supply means and said burners, normally upright generator pans fixedly related to said burners, said shafts being rotatably journaled in said frame, and means for rotating the shafts to bring the generator pans to horizontal generating positions.

6. An aggregate moisture eliminator comprising a wheel supported frame, beams extending transversely of the frame, aggregate stirring plows carried by said beams, with the plows of one beam offset laterally of the plows of an adjacent beam, transverse shafts carried by the

- frame in the rear of said beams, burners mounted on said shafts rearwardly of the stirring plows for heating the aggregate stirred by the plows, to eliminate moisture from the aggregate, fuel supply means carried by the frame, fuel connections between the fuel supply means and said burners, normally upright generator pans fixedly related to said burners, said shafts being rotatably journaled in said frame, means for rotating the shafts to bring the generator pans to horizontal generating positions, and means for latching the said shafts against accidental rotation, with the burners in substantially upright positions.
7. An aggregate moisture eliminator comprising a portable frame structure adapted to be moved over a bed of aggregate, aggregate stirring tools carried by the frame structure, burner means associated with the aggregate stirring tools for heating the aggregate stirred by the tools, to eliminate moisture from the aggregate, rear supporting wheels for said frame, a truck in advance of the frame, a beam connection loosely connected with the truck and the frame, manually actuated means cooperable with said beam connection and the frame for raising and lower-

ing the forward end of the frame, to vary the stirring depth of said tools, and manually actuated means for raising and lowering the rear end of the frame.

8. An aggregate moisture eliminator comprising a portable frame structure adapted to be moved over a bed of aggregate, aggregate stirring tools carried by the frame structure, burner means associated with the aggregate stirring tools for heating the aggregate stirred by the tools, to eliminate moisture from the aggregate, rear supporting wheels for said frame, a truck in advance of the frame, a beam connection loosely connected with the truck and the frame, manually actuated means cooperable with said beam connection and the frame for raising and lowering the forward end of the frame, to vary the stirring depth of said tools, manually actuated means for raising and lowering the rear end of the frame, said last-named means including a rotary crank axle for said wheels, and hand wheel means connected with the crank axle for rotating the latter.

ALBERT C. KENNEDY. 25
